Fig. 1

The screenshot shows a web-based application interface for managing a database of contacts. The top navigation bar includes links for Pages, ABOUT, Site, Tools, Help, Upgrade, and a search bar. The main menu on the left provides access to Site Structure, Pages, Print, Beaker, Databases, and Help/About. The current view is a table titled 'Contacts' with the following data:

	Name	Phone Number	Email	Image	Permissions
1	Dana	234567890 +055-1234567890	dana@wik.com		
2	Alex		alex@wik.com		
3	Felipe	Wrong phone number format	felipe@wik.com		
4	Gregory	234567890	greg@wik.com		
5	John	234567890	john@wik.com		
		+			

Below the table, there are buttons for Add Row, Visible Fields, Filter, Sort, Sync, Hooks, and Permissions. A 'Save' button is located at the bottom of the table area. The right side of the interface features a sidebar with 'Edit Live Database' and other navigation links.
